UNITED STATES PATENT OFFICE.

HERMAN SAUTER, OF CHICAGO, ILLINOIS, ASSIGNOR OF THREE-FOURTHS TO HERMAN I. NAGER, OF CHICAGO, ILLINOIS.

PAPER-INTERLEAVING MACHINE.

No. 902,838.

Specification of Letters Patent.

Patented Nov. 3, 1908.

Application filed May 9, 1908. Serial No. 431,882.

To all whom it may concern:

Be it known that I, HERMAN SAUTER, a citizen of the United States, residing at Chicago, in the county of Cook and State of Illinois, have invented a certain new and useful Improvement in Paper-Interleaving Machines, of which the following is a specification.

This invention relates to paper interleaving machines and is an improved mechanism for performing the folding and packing operations which are performed by similar mechanism in United States Patent No. 867,159, issued September 24, 1907 to Herman I. Nager as the assignee of Herman Sauter.

The object of this invention is to provide a new mechanism for taking cut and creased cigarette or toilet paper as it comes from a cutting and creasing mechanism and folding and packing the same into a pile of interleaved paper.

The invention consists in a chute for the paper combined with a set of packing fingers movable in novel paths which assist in placing the paper in proper position for packing and then do the desired packing, this with and without the added combination of latches for holding the paper in packed position while the packing fingers withdraw from contact with the paper.

The invention more in detail consists in novel mechanism for moving the fingers so that it may successfully perform the operation in the manner above suggested and in other details of construction which will be hereafter more fully described and claimed as the specification proceeds.

Figure 1 is a front view of a machine embodying this invention in its preferred form. Fig. 2 is a detail view of parts to be hereafter described. Fig. 3 is a side view of the entire machine and Fig. 4 is a rear view corresponding to Fig. 1 taken from a point in front of the fly wheel as seen in Fig. 1. Fig. 5 is another detail view of certain operating parts which will be hereafter described. Fig. 6 is a plan view on approximately the line 6—6 of Fig. 1, the chute not being shown in section. Figs. 7, 8 and 9 are sectional detail views on the line A—A of Fig. 3 showing the parts in various positions which they assume during the operation of the machine. Fig. 10 is a sectional detail view showing the mechanism for moving the packing fingers

into and out of the chute. Figs. 11 and 12 are enlarged detail views showing different positions of the paper and packing fingers.

The machine is mounted upon a table 15 supported upon suitable legs or standards 16. From this table at opposite ends rise end frame members 18 on which is mounted mechanism for cutting and creasing paper, in this instance being the mechanism of said prior patent. This mechanism broadly speaking comprises four shafts 20 and 21 carrying rollers 23 equipped with cutting and perforating knives 24 and fingers 25 operating to deliver strips of paper 27 in the form of combined cut and creased paper at 70 the point 30 said paper then being as fully set forth in said prior patent ready to be folded in zig zag form within the chute hereafter described. The paper 27 is primarily obtained from rolls (not shown) 75 mounted on the upper or cut away portions of the angular uprights 31. Through the table 15 is cut a relatively elongated opening or slot having the sides 34 and ends 35. Centrally located within this opening is a 80 chute or passageway 38 into which the paper fed down to position 30 by the cutting and creasing mechanism is adapted to pass through opening 40 between guard plates 41. The chute is rigidly mounted on the 85 table by stub shafts 43 on the chute entering the castings 44 secured to the table 15 by any suitable means.

Briefly summarizing the foregoing it will be seen that the chute projects upward 90 through the table adjacent to the point 30. As the remaining part or parts of the machine are duplicated (but reversed) on each side of the chute a description of those on one side will be sufficient. Upon each shaft 95 20, to which power is communicated from flywheel 46 by gearing 47 or any suitable means, is a sprocket wheel 49 over which passes a chain 50 engaging a pinion 51 mounted upon a shaft 52 journaled low 100 down in the end frames. This sprocket chain is kept at proper tension by the idle tension wheel 53 adjustably mounted by means of the block 54 and the bolt or pin 55 passing through elongated slot 56 in said 105 block 54. The result of this construction is that power in each shaft 20 is transmitted to the adjacent shaft 52 from which it follows that as the shafts 20 control and regulate the speed at which the cut and creased 110

paper is delivered at the point 30 as hereafter described each shaft 52 rotates at a fixed rate of speed with reference to the speed of delivery of said cut and creased paper at and past the point 30.

As shown in Fig. 6 the chute is very much longer in proportion to its width than is the chute of the above mentioned prior patent, this so that relatively wide paper may be 10 folded into the chute and then after removal from the chute be cut crosswise into a plurality of piles of paper which are ultimately broken up into a plurality of small packages or bundles. This construction 15 greatly reduces the number of machines required to fold and pack a given quantity of finished product packages. In order that the machine may fold wide paper as described a great many of the packing parts 20 are duplicated along the length of the chute, with the result that the drawings make the machine appear much more complicated than it really is. The construction will be 25 readily understood by the description, in general, of only one of these parts on a given side.

Latches and latch operating mechanism.—Between each shaft 52 and the adjacent wall of the chute 38 is a small shaft 58 on 30 which is rigidly mounted one or more upright levers 59 at the upper end of which is a pivotal bearing 60 on which is pivotally mounted a horizontal latch member 61 of such a length that its point 62 is adapted to 35 alternately enter and be wholly withdrawn from the adjacent inner wall of the chute in the same manner that corresponding latches enter the walls of the chute shown in said prior patent. In order to hold these 40 latches in a relatively fixed position and in contact with the upper surfaces of slots in the wall 38 through which the point 62 passes in entering and withdrawing from the chute, a coiled spring 64 is provided at 45 tached to the end of the latch member 61 and the lever 59 as shown. The point 62 of the latch 61 is normally spring pressed inside the chute by the coiled spring 66 attached at 67 to the lever 68 and to the adjacent edge 34 of the opening in the table. 50 Where more than one latch 61 is used they are as shown spaced some little distance apart along the chute. The distance to which each latch point 62 enters the chute is limited by 55 stop 69 rigidly connected by any suitable means to the lever 70 carried by the shaft 58. In other words the spring 66 normally forces the point 62 of the latch 61, as far into the chute as the stop 69 will allow it to go. 60 Pivottally connected to the lever 70 at 71 is a horizontal rod 72 having on its outer end a hook 73 adapted to catch upon pin or post 74 rigidly mounted upon the table as shown at a point outside the shaft 52. Upon 65 this shaft 52 is mounted a compound cam 76

having a tooth 77 adapted to engage the underside 78 of the rod 72 and, as the cam rotates, lift said rod 72 off from the post 74 upon which the rod has previously been hooked as is shown at the right of Fig. 7 70 and at the left of Fig. 8. This cam also carries a block 80 (best seen in Fig. 5) adapted to engage a depending lug 81 upon the adjacent bar 72 and as the cam is rotated, move the bar, contrary to the action of the 75 spring 66 into the latched position just referred to. Each block 80 and the teeth 77 are so shaped and located that when the hook 73 is over the end of post 74 the points 62 of connected latches are held entirely out 80 of the chute for a sufficient length of time so that paper folding mechanism, to be hereafter described, working adjacent to the particular latch (or latches) may force the freshly folded paper down below the plane 85 of the latch 61 after which the member 77 engages rod 72 and unhooks it from post 74, upon which the spring 66 instantly throws the latch or latches 61 into the chute over the freshly folded paper so that the folding 90 mechanism may withdraw without the new fold in the paper being released and thereby spoiled. The cams 76 on opposite sides of the machine are so located with reference to each other that these operations take place 95 alternately on opposite sides of the chute exactly as in said prior patent.

Folding mechanism.—Vertically slidably mounted in any suitable guides upon the upper portions of the walls of the chute are 100 two rods or bars 79^a each carrying at its upper end a head 80^a—81^a provided with an elongated parallel sided slot 82. Adjacent to each head which in this particular machine is longer than the others is a guide rod 83 made 105 in the particular case shown as one side of the slot.

Running through the slot 82 in the head 80^a located on a given side of the machine is a rod 85 on which is rigidly mounted a plurality of packing or folding fingers 86 adapted to enter the walls of the chute through notches 87. The notches for successive fingers 86 are staggered with or placed between the latches 61 heretofore described. 110 Rigidly attached to each rod 85 is one or more arms 89 (best seen in Fig. 2) having thereon an angular portion 90 on which are fingers 91 and 92 passing on opposite sides of the rod 83 with the result that as the rod 115 85 with attached parts is moved backward and forward horizontally in the slot 82 the rod 85 is held against rotation and consequently any given point on any part attached to the rod 85 moves horizontally with 120 reference to the rod 83 and of course moves horizontally with reference to the other parts of the machine whenever the heads 81 are stationary. The rod 85 is moved horizontally in the slot 82 by the following mechan- 125 130

ism (Fig. 10). On the adjacent shaft 52 is an eccentric 95 inclosed by an eccentric band 96 attached to a connecting rod 97 which is in turn pivotally connected at 98 to a vertical lever 100, pivoted at 101 upon a lug 102 mounted upon one side of the chute. In the upper portion of lever 100 is an elongated slot 104 through which the adjacent rod 85 passes from which it is seen the rod 85 may be raised and lowered a distance equal to the length of this slot without interfering with the reciprocating horizontal motion given to it by the lever 100 acting under the influence of power from shaft 52. The rod 85 is raised and lowered by the following mechanism; the bars 79^a are normally spring urged upwards by springs 106 which are resisted by a horizontal lever 107 adjustably pivoted at 108 engaging the bar 79^a on the plates or lugs 110, and a cam 112 also mounted upon the shaft 52. This cam has a face 113 so shaped that when it is in contact with the adjacent lever 107 the bar 79^a connected therewith will be held in depressed position and it has another face 113^a so shaped that when it is in contact with lever 107 the attached bars 79^a will move to highest position under the action of the spring 106. As the shaft 52 rotates cam 112 simultaneously with cam 76 it follows that this mechanism just described causes the rod 85 to travel up and down in slot 104 during a portion of the reciprocation of lever 100 and to remain at rest in lowered position during the remainder of the movement of the lever, with the result that the real path of travel of the center of rod 85 is substantially that of the dotted paths 114 and 115 shown in Fig. 10; the direction of travel of the rods on opposite sides of the machine being as indicated by the arrow heads viz. clockwise at the left and counter clockwise direction at the right. The cams and other parts on opposite sides of the machine are so located with reference to each other that the rods 85 on opposite sides always occupy exactly opposite or opposing portions of their respective paths 114 and 115. As all of the parts attached to the rod 85 move absolutely in unison and parallel to it the packing fingers 86 move in paths parallel to paths 114 and 115, that is to say assuming that the mechanism described has elevated them as high as possible and they are withdrawn as far as possible from the chute, they move into the chute horizontally for some distance and then gradually descend across the chute to a point at which they depress the paper (as shown on the left hand side of Fig. 8) sufficiently so that it is possible for the latch members 61 which have previously been withdrawn from the chute to spring in over the freshly pressed paper after which the fingers 86 are horizontally withdrawn from the chute in a horizontal line corresponding

to the bases of the paths 114 and 115 and finally returned by any suitable path to original position. It may be clearly and fully stated here that the path of travel in returning from the lower position to the upper position is entirely immaterial and is therefore represented by vertical straight lines in paths 114 and 115 although the actual path of travel may in this particular machine be slightly different. It is to be noted that the lower or packing faces of the fingers 86 are not horizontal but are inclined at a slight angle to the horizontal thereby readily assisting the packing and pressing down of the paper in the manner described more satisfactorily than perfectly horizontal fingers would work.

Figs. 7, 8, 9, 11 and 12 illustrate the successive positions of the packing fingers and the paper. Fig. 12 is an enlarged detail view of the fingers and paper in the same position as Fig. 8. The operation of the device will be most clearly understood by giving to the cut and crease in the incoming paper, which is at position 30 of Fig. 7 heretofore described a numeral as 120 and giving it the same numeral in the other figures so long as it is engaged by the left hand packing fingers and then when the right hand packing fingers begin to work on it giving it the numeral 121. With this understanding the operation of the machine will be clearly understood by stating that the left hand fingers first cause joint 120 to successively assume the positions of Figs. 7, 11, 8 or 12, and 9 at which time the right packing fingers treat this same joint now numbered as 121 as shown and successively move it to positions of Figs. 9, 7, 11 and 8 or 12. It is of course understood that while the right hand fingers and other parts have been operating on the joint 121 the left hand fingers have been folding in another or second succeeding joint 120 in exactly the same way as the first one was. It must also be understood that the right hand fingers fold in right hand angles or joints 122 on the left hand side of the chute exactly as left hand fingers fold in joints 120 and hold joints 122, now numbered 123.

Particular attention is called to Figs. 11 and 12 which show the manner in which the ends 126 of the packing fingers 86 engage the end portion 127 of the incoming piece of paper and force it into place in the fold. The movements of the parts are so timed that the ends of the fingers engage the incoming paper about half an inch above its end and stay in contact with some part of the end position until it is in proper inter-folded position as described.

It will be particularly noticed that owing to the angularity of the packing fingers 86 the paper is well packed at the edges adjacent to the points where the latches 61 are

90
95

100

105

110

115

120

125

130

snapped in without unduly at the same time pressing down the portion of the paper which is in the center and the portion of the paper which is toward the opposite side of the chute thereby not interfering with the natural incoming motions of the paper, this being quite important because of the fragile character of the paper packed.

The claims are:

1. In a device of the class described, the combination of a chute in which paper is to be packed, means for delivering cut and creased paper in condition to be packed at a point adjacent to the entrance of said chute, packing fingers mounted on opposite sides of the chute carried by operating mechanism capable of causing said fingers to alternately enter the chute, gradually descend downwardly across the chute to fold paper at the opposite side of the chute, pack down paper within the chute and then withdraw from the chute without interfering with further folding and packing operations within the chute.

2. In a device of the class described, the combination of a chute in which paper is to be packed, means for delivering cut and creased paper in condition to be packed at a point adjacent to the entrance of said chute, packing fingers mounted on opposite sides of the chute carried by operating mechanism capable of causing said fingers to alternately enter the chute, gradually descend downwardly across the chute to fold paper at the opposite side of the chute, pack down paper within the chute at the edges of the chute on which the respective packing fingers are located and then withdraw from the chute without interfering with further folding and packing operations within the chute.

3. In a device of the class described, the combination of a stationary chute in which paper is to be packed, means for delivering cut and creased paper in condition to be packed at a point adjacent to the entrance of said chute, packing fingers mounted on opposite sides of the chute carried by operating mechanism capable of causing said fingers to alternately enter the chute, gradually descend downwardly across the chute to fold paper at the opposite side of the chute, pack down paper within the chute and then withdraw from the chute without interfering with further folding and packing operations within the chute.

4. In a device of the class described, the combination of a chute in which paper is to be packed, means for delivering cut and creased paper in condition to be packed at a point adjacent to the entrance of said chute, packing fingers mounted on opposite sides of the chute carried by operating mechanism capable of causing said fingers to alternately enter the chute, gradually descend

downwardly across the chute to fold paper at the opposite side of the chute, pack down paper within the chute and then withdraw from the chute without interfering with further folding and packing operations 70 within the chute, and mechanism capable of engaging and holding paper just folded in while the folding fingers are being withdrawn.

5. In a device of the class described, the combination of a chute in which paper is to be packed, means for delivering cut and creased paper in condition to be packed at a point adjacent to the entrance of said chute, packing fingers mounted on opposite 80 sides of the chute carried by operating mechanism capable of causing said fingers to alternately enter the chute, gradually descend downwardly across the chute to fold paper at the opposite side of the chute, pack down 85 paper within the chute at the edges of the chute on which the respective packing fingers are located and then withdraw from the chute without interfering with further folding and packing operations within the 90 chute, and mechanism capable of engaging and holding paper just folded in while the folding fingers are being withdrawn.

6. In a device of the class described, the combination of a stationary chute in which 95 paper is to be packed, means for delivering cut and creased paper in condition to be packed at a point adjacent to the entrance of said chute, packing fingers mounted on opposite sides of the chute carried by operating mechanism capable of causing said 100 fingers to alternately enter the chute, gradually descend downwardly across the chute to fold paper at the opposite side of the chute, pack down paper within the chute 105 and then withdraw from the chute without interfering with further folding and packing operations within the chute.

7. In mechanism of the class described, a receptacle in which paper is to be packed 110 and means for delivering cut and creased paper thereto; a packing finger adapted to enter and be withdrawn from a wall of said receptacle said finger being of such a length that when in forward position it extends approximately across the chute, means for moving said packing finger parallel to the central axis of said receptacle, means for moving said packing finger transversely to the central axis of said receptacle, said two 115 120 means being so combined that the resultant motion of the packing fingers is first inward within the receptacle and thence downward and across it and then finally out of the receptacle.

8. In mechanism of the class described, a receptacle in which paper is to be packed, and means for delivering cut and creased paper thereto; a packing finger adapted to enter and be withdrawn from a wall of said 130

- receptacle said finger being of such a length that when in forward position it extends approximately across the chute, means for moving said packing finger parallel to the 5 central axis of said receptacle, means for moving said packing finger transversely to the central axis of said receptacle, said two means being so combined that the resultant motion of the packing fingers is first inward 10 within the receptacle and thence downward and across it and then finally out of the receptacle, the lower or packing face of said finger being inclined upward toward its point as described.
- 15 9. In mechanism of the class described, a receptacle in which paper is to be packed and means for delivering cut and creased paper thereto; a packing finger adapted to enter and be withdrawn from a wall of said receptacle, means for moving said packing finger parallel to the central axis of said receptacle, means for moving said packing finger transversely to the central axis of said receptacle, said two means being so combined that the resultant motion of the packing fingers is first inward within the receptacle, thence downward and across it and then finally out of the receptacle, and a latch member normally entering the receptacle combined with mechanism operating in unison with the finger operating mechanism for temporarily withdrawing the latch member as the packing finger reaches its lowest inclined position within the receptacle.
- 35 10. In mechanism of the class described, a receptacle in which paper is to be packed, and means for delivering cut and creased paper thereto; a packing finger adapted to enter and be withdrawn from a wall of said receptacle, means for moving said packing finger parallel to the central axis of said receptacle, means for moving said packing finger transversely to the central axis of said receptacle, said two means being so combined that the resultant motion of the packing fingers is first inward within the receptacle, thence downward and across it and then finally out of the receptacle, and a latch member normally entering the receptacle combined with mechanism operating in unison with the finger operating mechanism for temporarily withdrawing the latch member as the packing finger reaches its lowest inclined position within the receptacle for 55 the purpose set forth.
11. In a machine of the class described, the combination of a paper receptacle or chute, a latch normally entering one wall of said chute, rotatable cam mechanism capable of temporarily withdrawing the latch from the chute and mechanism operable by the cam for locking the latch in withdrawn position and finally releasing it from said locked position.
- 60 65 12. In a machine of the class described,
- the combination of a paper receptacle or chute, a latch member slideable through one wall thereof, mechanism normally spring pressing said latch member into the chute, a fixed member at one side of the chute, a 70 member connected to the latch member having a hook adapted to engage said fixed member and cam mechanism capable of withdrawing said latch member from the chute and hooking said hook over said fixed member for thereby holding said latch member in withdrawn position, and mechanism upon said cam for later automatically unhooking said connecting member and thereby releasing the latch member.
13. In a machine of the class described, the combination of a paper receptacle or chute, a lever pivotally mounted adjacent to one wall of the chute, a latch pivotally mounted upon said lever entering said chute 85 through the wall, a stop limiting the distance which said latch can enter the chute, means for spring pressing said latch into the chute to the limit allowed by said stop and rotatable cam mechanism capable of temporarily withdrawing said latch from the chute and holding it in withdrawn position.
14. In a machine of the class described, the combination of a paper receptacle or 90 chute, a lever pivotally mounted adjacent to one wall of the chute, a latch pivotally mounted upon said lever entering said chute through the wall, a stop limiting the distance which said latch can enter the chute, 95 means for spring pressing said latch into the chute to the limit allowed by said stop, and cam mechanism capable of temporarily withdrawing said latch member from the chute and temporarily locking it upon a fixed support in withdrawn position and capable of finally releasing said latch member.
15. In mechanism of the class described, the combination of a paper receptacle and a latch normally spring urged into said receptacle against a stop limiting said motion, a rigid connecting member having one end connected to the latch member and at the other end a hook adapted to engage a fixed support, a compound cam so engaging said rigid member that during one portion of its stroke it moves said rigid member to a position in which said hook engages the fixed support thereby locking the latch in withdrawn position and there being a member 110 upon the cam also engaging said rigid member at a point further on in the rotation of the cam to automatically unlock said rigid member from the fixed support as described.
16. In mechanism of the class described, 115 in combination with a paper receptacle or chute, a lever pivotally mounted adjacent to one wall of the chute, a latch member carried by said lever member entering the chute, spring mechanism normally forcing said 120 125 130

- 6
- latch member into the chute against a stop limiting its motion, spring mechanism normally pressing said latch member laterally against one wall of the recess through which it enters the chute and cam mechanism designed to temporarily withdraw the latch member from the chute and lock it in withdrawn position upon a fixed support until released by another portion of said cam.
- 10 17. In mechanism of the class described, the combination of a paper chute, a head normally movable parallel to one wall of said chute having a recess therein transverse to the plane of the wall of said chute, a packing finger slidably mounted in the recess in the head, mechanism for automatically moving said head in a direction parallel to the wall of the chute, mechanism capable of moving said packing finger along said recess in the head transverse to the wall of the chute, said two moving mechanisms being so timed as to cause said packing finger to enter the chute at a given point, pass gradually across and down the chute to the opposite side and withdraw from the chute in the manner described.
- 15 18. In mechanism of the class described, in combination with a chute for paper, a rod slidably mounted upon the side of the chute, spring mechanism normally urging said rod in one direction, cam mechanism capable of moving said rod in the opposite direction, a head carried by said rod, a packing finger movable along said head transversely to the first direction of motion, and mechanism for reciprocating said packing finger along the rod simultaneously with the movement of the rod and attached head, with the result
- 20 that said packing finger moves into and out of said chute in a predetermined irregular path.
- 25 19. In mechanism of the class described, the combination of a cross head so mounted as to move along a wall of a paper chute, a rod extending through an elongated slot in said cross head and capable of being moved transversely of its own axis in said cross head along said slot and an arm connected to said rod engaging a guiding member adjacent to said cross head in such a way that the rod is moved along said guide in the cross head without rotating for the purposes specified.
- 30 20. In a device of the class described, the combination of a chute in which paper is to be packed, means for delivering cut and creased paper in condition to be packed at the entrance of said chute, a packing finger mounted adjacent to the chute adapted to enter the chute, gradually descend downward across the chute and then withdraw therefrom, means for so moving the finger so timed with reference to the speed of the incoming paper and to the length of the finger that the end of the finger engages the loose end of an incoming sheet of paper and moves it to position on the opposite side of the chute.
- 35 In witness whereof, I have hereunto subscribed my name in the presence of two witnesses.

HERMAN SAUTER.
